UNITED STATES PATENT OFFICE.

PATRICK J. GORMAN, OF HARRISON, NEW JERSEY.

GARMENT-HANGER.

1,245,901.

Specification of Letters Patent. Patented Nov. 6, 1917.

Application filed November 12, 1915. Serial No. 61,181.

To all whom it may concern:

Be it known that I, PATRICK J. GORMAN, a citizen of the United States, residing at Harrison, in the county of Hudson and 5 State of New Jersey, have invented new and useful Improvements in Garment-Hangers, of which the following is a specification.

This invention relates to garment hangers or supports adapted to be used in combination with trunks, wardrobes and the like, and it consists of the novel features 10 hereinafter described and claimed.

An object of the invention is to provide a device of the character described which 15 is of a simple structural arrangement and which may be easily and quickly manipulated or operated, when in a trunk, to move the garment or clothes supported by the same, beyond the forward portion or open 20 side of the trunk or receptacle in order that the garment may be adjusted or removed from the hanger, as desired.

Another object of the invention is to provide a structure of this character which will 25 consist of arms having relatively fixed sections which are secured to the inner walls of the trunk or receptacle, and swinging sections supported from the relatively fixed sections and adapted to be extended to positions where they will lie in the same general direction therewith when it is desired 30 to extend the garment supporting hangers to a position exteriorly of the trunk.

Another object of the invention is to provide 35 a device of this character which will include arms having fixed sections and swinging sections, and means for holding the latter against swinging movement when the trunk is closed.

40 In the drawings;

Figure 1 is a horizontal section through a trunk showing the application of the invention thereto.

Fig. 2 is a perspective view of the fixed 45 section of one of the arms.

Fig. 3 is a similar view of the swinging section of the arm.

Fig. 4 is a side view of the two sections 50 of the arm on an enlarged scale.

Fig. 5 is a vertical longitudinal section therethrough.

Fig. 6 is a perspective view of the hanger arm.

Fig. 7 is a perspective view of the attaching bracket.

The wardrobe A herein conventionally

illustrated, is of a character or form which is well-known and as illustrated; it is provided at one side with a swinging closure which consists of sections B—B that may 60 be adjusted at the convenience of the operator so that free access may be gained to the space within the trunk, as the occasion may demand.

The hanger or slide consists of arms 1—1, 65 each consisting of a relatively fixed section 2 and a swinging section 3. The fixed sections are provided with angular flanges 4 secured in any suitable well-known manner to the rear wall of the container. These 70 relatively fixed sections are each stamped up from a single piece of metal and they are each provided with a vertical side wall 5 which is curved outwardly and then downwardly along its upper edge to form a rail 75 surface 6. At the outer end the wall 5 is extended and turned to form vertically alined hinge loops 7 and from the loops the metal is bent over against the wall 5 and then terminally secured to the wall by a 80 rivet or the like 8, as clearly shown in Fig. 2. The swinging section 3 of each arm is also provided at one end with hinge loops 9 which are adapted to mate with the hinge loops 7 of the companion relatively fixed 85 section 2. A pintle 10 is then passed through the loops 7 and 9 so that the section 3 may be conveniently moved respectively into and out of the container A. The inner ends of the sections 3 of the arms are 90 provided with short transversely curved extensions 11 which are adapted to be continued directly onto the rail surfaces 6 of the arm sections 5. By reason of the fact that the sections 3 and the extensions 11 95 thereof are formed from sheet metal, the said extensions may flex and swing laterally over the sections 6 when the sections 3 are swung into alinement with the sections 5 notwithstanding the fact that the extensions 100 11 are slightly curved transversely. The said sections 3 are provided with rail surfaces 12 which are similar to the surfaces 6 and they are alined therewith horizontally when the sections 3 are adjusted to the dotted 105 line positions shown in Fig. 1, whereby the extensions 11 engage over the surfaces 6 and the parts are held in alinement.

The section 3 of the arm at the right of the container A is provided with a longitudinal slot 13 which receives a combined stop and actuating pin or stud 14 carried

by a sliding bolt 15. This bolt moves through a packing 16 in the head 17 of the said section 3 of the arm at the right in Fig. 1, and on reference to Fig. 5, it is observed that the bolt is provided with a stem 18 which is slidably received in a fixed guide bracket 19. A spring 20 encircles the stem 18 and it is interposed between the bolt 15 and the bracket 19 so that it normally exerts its action against the bolt to hold the same in a projected position. The head 17^a of the swinging section 3 forming part of the arm shown at the left in Fig. 1, is provided with a keeper passage 21 which is adapted to receive the bolt as shown in Fig. 5, and thereby hold both of the mentioned swinging sections 3 in the positions shown in Fig. 1, where they will be disposed substantially parallel to the swinging doors B—B.

Hanger bars 22 are mounted within the container A and these bars are adapted to freely slide on the supporting arms or brackets 1. These hanger bars are provided at their ends with hooks 23 having relatively flat branches 24 which are adapted to come against the inner faces of the sections 2 and 3 of the arms 1 when the hanger bars are moved to the dotted line positions shown in Fig. 1. The hooked ends 25 are adapted to freely pass over the rail forming surfaces 6 and 12 of the sections 2 and 3 and to slide thereon.

From the construction described it is evident that means are employed herein, whereby when the doors B—B of the container A are opened the sections 3 of the arms 1 may be swung to positions where they will extend in the same general direction as the sections 2. The hanger bars 22 are then capable of being freely adjusted to any point beyond the open side of the container so that the garment desired may be removed

from the hanger or adjusted thereon, as the occasion may demand. In order to limit the outward sliding movement of the forward hanger bar 22, the manipulating stop 14 is adapted to come in the direct path of movement of the outward adjustment of the bar, while a fixed stop pin 26 on the other swinging section 3 is adapted to come in contact with the hanger bar at the opposite end thereof. In this manner several of the bars 22 may be adjusted to points beyond the opening in the container A and the possibility of accidental derangement of the bars from the arms 1 is reduced to a minimum. After the bars 22 have served their purpose they may be very compactly arranged in the container A and the garments maintained in a neat and uniform condition. The sections 2 of the arms 1 are connected to the side walls of the container A by brackets 27.

What is claimed as new is:

A garment hanger comprising fixed arms, sections hinged thereto, said sections being formed from sheet material and having a transversely curved edge portion extending longitudinally thereof and provided at their inner ends with transversely curved extensions adapted to engage over the ends of the said arms, a rail mounted for sliding movement over the arms and sections, and a spring pressed bolt slidably mounted under the curved edge portion of one section and adapted to engage under the curved edge portion of the other section whereby the sections are locked together when swung into alignment with each other.

In testimony whereof I affix my signature in presence of two witnesses.

PATRICK J. GORMAN.
